POLE TYPE ELECTRICAL TRANSFORMER

Roger F. Schrader, Wilmer H. Airgood, and Gordon C. Nonken, Pittsfield, Mass., assignors to General Electric Company, a corporation of New York

Filed Mar. 3, 1965, Ser. No. 84,065

Term of patent 14 years

(Cl. D26—15)

Fig. 1.

Fig. 2.

Fig. 3.

FIGURE 1 is a front, top and right side perspective view of a pole type electrical transformer, showing our new design;

FIGURE 2 is a right side elevational view, to an enlarged scale, the opposite side being substantially a mirror image thereof; and

FIGURE 3 is a rear elevational view thereof, to an enlarged scale.

We claim:

The ornamental design for a pole type electrical transformer, as shown and described.
